UNITED STATES PATENT OFFICE.

EDGAR A. WANGERSHEIM, OF CHICAGO, ILLINOIS, ASSIGNOR TO GENERAL LIGHTING FIXTURE CO., OF CHICAGO, ILLINOIS, A CORPORATION OF ILLINOIS.

DESIGN FOR A LIGHTING FIXTURE.

Application filed January 27, 1923. Serial No. 5,010. Term of patent 7 years.

To all whom it may concern:

Be it known that I, EDGAR A. WANGERSHEIM, a citizen of the United States, residing at Chicago, in the county of Cook and State of Illinois, have invented a new, original, and ornamental Design for Lighting Fixtures, of which the following is a specification, reference being had to the accompanying drawing, forming part thereof.

The figure is a plan view of a lighting fixture, showing my new design.

I claim:

The ornamental design for a lighting fixture, as shown.

EDGAR A. WANGERSHEIM.
